UNITED STATES PATENT OFFICE.

NORMAN WIARD, OF NEW YORK, N. Y.

IMPROVEMENT IN THE CONSTRUCTION OF ORDNANCE.

Specification forming part of Letters Patent No. 38,709, dated May 26, 1863.

To all whom it may concern:

Be it known that I, NORMAN WIARD, of the city, county, and State of New York, have invented a certain new and useful Improvement in Ordnance; and I do hereby declare that the following is a full and exact description thereof, reference being had to the accompanying drawings, and to the letters denoted thereon.

Figure 1 is a longitudinal section. Fig. 2 is a cross-section on the line *s s* in Fig. 1. Fig. 3 is an end elevation. The right-hand side is part of a rear-elevation, with a portion broken away to exhibit its interior, and the left-hand side is part of a front elevation. Fig. 4 is a longitudinal section of an implement I have devised to facilitate the loading of this gun.

Similar letters of reference indicate like parts in all the figures.

The attainment of the greatest effect with projectiles, whether for a long range or for the penetration of iron armor, requires the highest velocity possible to be attained. To generate a very high velocity, the projectile must be acted on with great force, and this force must be maintained or continued through a great distance. In guns, as ordinarily constructed, the powder acts with great force at or near the early portion of the movement of the projectile along the bore, and then commences to act with diminished force during the latter part of such movement. The effect of such action is to generate a less velocity than if the powder, or rather the gases evolved therefrom, continued to act at its maximum force, or nearly so, during the entire movement of the projectile. My gun is provided with an enlarged chamber, that contains the powder, and from this powder is evolved a sufficient amount of gas to keep up a higher expansive force against the shot during the middle and latter portions of its movement in the bore than is attainable in guns as ordinarily constructed, and the use of this device is made practicable in large guns by devices for compensation for unequal expansion by heat, and by modes of attaining great strength.

To enable others skilled in the art to make and use my invention, I will proceed to describe its construction and operation by the aid of the drawings and of the letters thereon.

A is a lining of steel, constructed in the form represented, so that there is at the rear of the barrel a swell, *A'*, inclosing a chamber, *M*,

larger than the main bore of the gun. This chamber *M* is bored without difficulty by means known to workers in metal, and contains, in a form adapted to facilitate its rapid ignition, a much larger quantity of powder than can be burned with advantage behind a projectile in guns of the ordinary construction.

B is a covering of bronze, forced tightly upon the lining *A*. The inner surface of *B* and the outer surface of *A* are tapered slightly, the rear end of *A* being largest. This facilitates the production of a very tight fit of these parts; but care must be taken that the thickest part of the steel lining *A* be not too great. I prefer to make this thickness, if the gun be large, about three and a half inches, as otherwise the difference in the temperature between the inner and outer particles induces a serious strain.

C D E F are heavy washers of steel, prepared with a spring-temper and touching each other only at a few points by the aid of the projections *d*, *e*, and *f*, arranged each in a different part of the circle from the next, so as not to coincide in position, but to differ as widely each from the other as possible. This will be readily understood by a mechanic, and allows the elasticity of the washers to be brought into play.

G is a nut fitted upon the steel *A* by a screw-thread, as represented. This is applied against a washer, *F*, with considerable force, so as to compress or bend slightly—that is, to produce an elastic yielding or deflection—all the washers between itself and the washer *C* resting against the bronze *B*.

H is the partial inner shell, and *H'* the outer shell, of a bronze casting, which is forced or shrunk on over the parts before described. This casting is filled with lead, *J*, and compressed, and is provided with braces *H'*, which connect the inner metal, *H*, with the outer shell, *H'*. A quantity of lead, *K*, is also introduced between this casting and the swell *A'*, which contains the spherical chamber, and is held by a screw, *L*.

My arrangement of the steel lining *A*, which is hard and but slightly expansible by heat, within the shell *H H' H'*, which is more expansible by an equal degree of heat, and is consequently equally expanded with a less degree of heat, allows the exterior metal to aid

in resisting the mechanical force of the gases, and yet allows the several metals to expand naturally with heat as the heat is generated in the interior and diffused through the mass without very considerably increasing the strain on any portion. This is a vitally-important element in my invention. In addition to the above, my gun stores in its capacious chamber M so large a quantity of powder, and allows it to burn so quickly, that the great initial pressure, which is usually felt by the projectile during only the early portion of its movement, is continued farther than usual toward the muzzle, acting a greater length of time against the shot, to accelerate its motion. The action in this respect may be compared to, but in an almost inconceivably-greater extent than, the motion of mercury in the tube of a common thermometer, due to the expansion of the large quantity of mercury contained in the bulb. If a thermometer were constructed without the bulb, the expansion of the mercury in the tube only would not be sufficiently apparent to give room for graduations; but by the addition of the quantity in the bulb, affected by the change of temperature, the motion along the tube is very great, and can be proportioned to give any required amount of motion in the tube if the bulb could be made to resist the forces acting upon it. An equally-large quantity of powder may be placed behind a projectile in a gun of ordinary construction as in mine, provided the bore of such ordinary style of gun be made of very great length, and a large proportion of its length be filled with powder; but in such case the powder is not entirely burned before the projectile escapes from the muzzle, because the powder is in a long and comparatively slender column, and time is required for fire to communicate through powder. In my chamber M the same quantity of powder which would in a uniform bore consume too much time in igniting to be fully effective is all ignited in time to be of service.

The vent of my gun passes through the material and communicates with the interior of the chamber M on its front side, very near the junction between the chamber M and the ordinary cylindrical portion of the bore of gun. By reason of this position of vent, (not represented,) the fire is communicated to the cartridge on its front side, and by the ignition of the powder at that point the remainder of the powder is held back in its place, and the flame alone is projected forward. This allows a larger surface for the ignition of the cartridge as the process of ignition proceeds, and is, for many reasons, preferable to the ordinary mode of driving forward the whole or a portion of the powder with the ball. These are exactly the conditions required in a gun to attain the highest velocity. I believe my mode of constructing this gun will allow the successful use of this idea; but with an enlarged chamber, M, without my plan of compensation, the structure would be destroyed by the joint effects of the high mechanical

pressure and the heat to which it would be subjected. To retard the communication of heat from the powder within M to the walls of the chamber, I propose to line the chamber with properly-prepared clay or other suitable non-conducting substance, in the manner represented by *m* in Fig. 1. This is allowable in this portion of my gun more than in the bore of ordinary guns, for reasons which will be obvious; but I do not consider such a non-conducting lining necessary in most cases, if the compensating devices described are properly constructed and proportioned.

The instrument represented in Fig. 4 and the modifications of the wad, &c., which I esteem important in loading my gun may be very readily understood.

N is a cylinder of copper, and *n* is a hollow wooden stock by which it may be reached into the gun. *n'* is a stop which rests in and against the muzzle when the loader is fully in place. The cubical contents of *N* are equal to those of the chamber M of the gun.

An elastic disk or wad, *O*, is placed upon the convex face of the plunger *P*. Then the powder for a charge is next introduced into *N*; next, a sheet of paper, *R*, is placed over the end of *N*, and, lastly, a ring, *S*, is slipped over the edges of the paper, holding it strongly to *N*. The loader and its contents are next introduced into the gun, until the stop *n'* rests on the muzzle. The plunger *P* is then forced inward by the rod *p*, passing through the stock *n*, bursting the paper *R*, and shoving the powder *Q* into the large chamber M of the gun, and also forcing the wad *O* in and allowing it to expand therein, so that it will retain the powder. The loader is now withdrawn, and the ball introduced in the ordinary manner. These devices avoid the trouble which might be met with in attempting to fill my chamber M with powder by any of the ordinary means, as it would evidently involve much labor to elevate the piece into a perpendicular position in order to fill such chamber by gravity.

My gun may be mounted on trunnions and operated in any approved manner; but I prefer to locate the trunnions nearer the rear end or breech than the center of gravity, as is indicated in Fig. 1, and to operate an elevating-screw at some convenient point near the muzzle. The preponderance will in such case be made very great, and in the front, instead of the rear, of the trunnions.

Some of the advantages due to separate features of my invention may be separately enumerated, as follows:

First. By my chamber M, larger than the bore, in combination with my inner shell, *H*, outer shell, *H'*, and braces *H''*, I am able to burn a greater quantity of powder behind a given projectile with good effect than by any means before practicable, and to thus generate and continue upon the projectile a very great propelling force without too seriously straining the metal of the gun.

Second. By my bronze piece B, intermediate between the lining A and the exterior bronze, H H' H'', or its equivalent, I am able to construct the lining A, having the bulb or swell for the chamber M, and with its smaller bore or barrel all of equal or nearly equal thickness throughout, and to have the whole so thin that the heat may properly permeate it, and am able, also, to tightly fill the entire cavity in the exterior bronze. By this I am able to force the lining A and bronze intermediate piece, B, into the exterior shell as tightly as may be desired. Without this or some equivalent provision I believe it impracticable to fully realize all the advantages due to the use of the chambered lining A M within a compensating shell, H H' H'', because the lining would require to be much thicker along the barrel than around the chamber, or else would not be properly supported by the said shell.

Third. By the employment of the elastic washers C D E F, arranged as represented relatively to the lining A, with its swell containing a chamber, A, and relatively, also, to the intermediate piece, B, and nut or stop G, I am able to hold the piece B firmly against the forward surface of the swell, and to allow it to

expand and contract longitudinally with heat to a different extent from the lining A.

Having now fully described my invention, what I claim as new therein, and desire to secure by these Letters Patent, is—

1. The chamber M or an equivalent enlargement at the breech of a slightly-expansible lining, A, in combination with the means of compensating for unequal heating and resisting great strain, substantially as represented by B, H, H', and H'', for the purpose above set forth.

2. In guns with a lining, A, having a swell and chamber at its breech, the employment of the piece B, of a material more expansible by heat than A, between the lining A and the exterior shell, H, or its equivalent, for the purpose herein set forth.

3. Allowing independent longitudinal expansion of the piece B by means of the washers C D, &c., made elastic, substantially as described.
